UNITED STATES PATENT OFFICE.

TOBIAS E. RAFFEL, OF NEW YORK, N. Y., ASSIGNOR TO PAPER WORKING MACHINES CO., A CORPORATION OF NEW YORK.

TAPING-MACHINE.

1,080,779.

Specification of Letters Patent. Patented Dec. 9, 1913.

Application filed February 4, 1913. Serial No. 746,108.

To all whom it may concern:

Be it known that I, TOBIAS E. RAFFEL, a citizen of the United States, and residing in the city, county, and State of New York, have invented certain new and useful Improvements in Taping-Machines, of which the following is a specification.

The invention relates to a tape applying machine and more particularly to improvements in the construction, arrangement and organization of the parts thereof.

One object of this invention is to provide a machine having a novel combination of tape feeding, severing and applying mechanisms, co-operating to intermittently feed the tape, sever a portion of desired length therefrom, and apply the severed portion to the work by a rotary movement of the tape applier.

Another object of the invention is to provide novel work feeding means, co-acting with the tape applying mechanism to feed the work into position to receive the tape thereon.

A further object is to provide a construction whereby the parts of the machine may be rapidly and accurately adjusted to permit of the tape being deposited at any desired point on the work.

In the accompanying drawings illustrating the preferred form of the invention, Figure 1 is a side elevation of the machine; Fig. 2 is an end elevation looking from the front; Fig. 3 is a plan view; Fig. 4 is a detailed view of the device for adjusting the taping mechanism; Fig. 5 is a detailed view of the adjustable cam of the tape severing mechanism; Fig. 6 is a detailed view of the tape applying mechanism, showing the gripper in closed position; Fig. 7 is a fragmentary view of the tape applier, showing the gripper opened, and Fig. 8 is a detailed plan view of the tape applier.

In the illustrated embodiment of this invention, the tape (1) is intermittently fed by suitable feeding means on to the face of the constantly rotating taping drum (2) where it is automatically engaged in the gripper (3) and drawn from the supply spool (4). As the tape is being thus drawn, the knife (5) is actuated to cut a piece of desired length therefrom. The severed portion of tape is carried by the rotation of the drum toward the object on which it is to be applied, which in the meantime is being au-

tomatically fed through the machine by means of a suitable work feeding mechanism. At the point of contact between the drum and the object, the gripper is automatically opened to release the tape and permit of its application upon the object.

The tape feeding means consist of a driving roll (6) and an idler (7) spaced apart and formed with circumferential grooves (8) through which the tape guides (9) project. The driving roll (6), which is geared to rotate in unison with the drum (2), is provided with two segments (10), disposed on either side of the lower guide (9), which serve to press the edges of the tape against the idler (7) and by rolling frictional contact therewith to intermittently advance the end of the tape to a point above the face of the drum. The tape, in feeding, passes between two freely rotating toothed rolls (11) which serve to crack the adhesive coating of the tape and thereby prevent it from curling.

To press the end of the tape down upon the surface of the drum in position for engagement by the gripper (3), I provide a mechanism comprising a hinged presser plate (12) located above the tape and arranged to be raised and lowered by the movement of the forked rod (13) having the laterally projecting pin (14) which rides on the recessed cam disk (15) rotating with the drum (2). The cam is set with relation to the rotation of the drum so that the operation of this mechanism will be timed to 90 press the end of the tape upon the drum just before the gripper is brought into position to engage it.

The tape gripping means, as best seen in Figs. 6, 7, and 8, consist of a gripper (3) rigidly fixed to the transversely extending spindle (16) which is mounted for oscillation in a bearing block (17) secured to the inner face of the rim of the drum (2). The spindle has a crank arm (18) which is secured at its end to a rod (19) mounted for combined endwise and lateral swinging movement in a support (20) attached to the drum (2). A spring (21), coiled around the rod (19) and fastened at its ends respectively to the support (20) and the sleeve (22) fixed to the rod, is provided to thrust the gripper into gripping position, as hereinafter described. The outer end of the spindle has an enlarged head (23) carrying 110

an outwardly projecting segment (24). In Fig. 6 the gripper is shown in closed position just after it has engaged the end of the tape. From an inspection of this figure it will be seen that as the drum rotates in the direction of the arrow, the end (a) of the segment (24) will strike the pin (25), which is rigidly held in the path thereof and thereby cause the spindle to turn in its bearing so as to throw the gripper (3) into open position, shown in Fig. 7, and release the end of the tape. When the end (b) strikes the upper rigidly held pin (26), the spindle will be caused to turn in the opposite direction, thereby carrying the center of the crank arm (18) off the center of the rod (19) and permitting the spring (21) to expand to drive the rod (19) upward and the gripper (3) downward upon the edge of the resilient plate (27) so as to firmly clamp the end of the tape which in the meantime has again been fed into position. The plate (27) is secured for slight sliding movement in a recess formed in the face of the drum, and is resiliently held therein by the springs (28), as clearly seen in Fig. 8. This construction permits the plate to move backward from under the gripper when the latter is driven home upon it, and to thereby counteract the tendency of the gripper to recoil.

The tape severing mechanism consists of a bell crank (29) pivoted as at (30) and provided, at the end of its vertical arm, with a lug (31) which is pressed against the face of the notched cam (32) by means of a spring (33) drawing on the horizontal arm of the crank. The rear end of the latter arm is connected by a compound lever (34) with the knife (5) so that when the lug (31) enters the notch in the cam, which is arranged to rotate with the drum, the knife will be operated to cut a strip from the tape. The cam is fastened by a nut (35) screwed on the threaded end of the bolt (36) which is fixed to the drum and projects through the segmental slot (37) of the cam. When the nut is loosened, the cam may be independently rotated to adjust the position of the notch so as to time the actuation of the knife to sever a portion of any desired length from the tape.

In order to moisten the adhesive surface of the tape, I provide a water wheel (38) which is rotated in the trough (39) and conveys the water to the freely turning fountain roller (40) by which it is applied to the strip while it is being carried on the drum. The wheel (38) is preferably mounted in a sliding box so that its position can be adjusted toward or away from the fountain roller to vary the quantity of moisture supplied.

The form of machine herein described is particularly designed to apply a strip of adhesive tape upon the seam of a folded box

blank so as to unite the parts thereof. At the front end of the machine is located a work supporting table (41) upon which a stack of blanks may be placed in the hopper formed by the two laterally adjustable wings or gages (42) so that the seams of the blanks will be in line with the center of the taping drum (2). A laterally adjustable pressure shoe (43), having a weight (44) at the end, is provided to keep the blanks flat in the hopper.

To feed the blanks a pusher blade (45) is employed, and provision is made for actuating the blade to successively push the lowest blank of the stack into the machine. The blade (45) extends across table behind the rear edge of the bottom blank and is provided, at the ends, with pins (46) which fit into gage holes (47) formed in the bars (48) whereby the position of the blade may be accommodated to the length of the blank. The bars (48) are slidably supported in the ways (49) disposed at the sides of the table (41) and are each connected by a link (50) with one of the upwardly extending arms (51) which are fixed to the rock shaft (52). One end of the rock shaft is provided with a lever (53) which is connected by a rod (54) to the crank (55) of the power driven rotary cylinder (56). The rod (54) is preferably divided into two parts connected by a turnbuckle (57) whereby the length of the stroke may be readily adjusted. At each revolution of the cylinder, the pusher blade is operated to move forward on the table to thereby shove one of the blanks upon the cylinder and then returned to its initial position for engagement with the next blank. The cylinder (56) is mounted directly below the taping drum with its axis parallel thereto and serves to support and advance the blank while the adhesive strip is being applied thereon by the rotary movement of the drum.

The tape applying, feeding, cut off and moistening mechanisms are all preferably mounted in a single carriage (58) which may be moved bodily, from side to side, to afford lateral adjustment. The carriage is rigidly fixed to two parallel shafts (59) which are provided with racks (60) at their right hand ends and supported for endwise movement in the frame (61) of the machine. A spindle (62) carrying two pinions (63) which mesh with racks (60) and having a hand wheel (64) is provided to effect the lateral adjustment of the carriage.

The taping drum (2) is firmly secured to a shaft (65) which is given a continuous rotary movement by the gear (66) fixed to rotate with the power driven cylinder (56) and meshing with the gear (67) which turns loosely on the shaft and has an attached disk (68) keyed to slide in the slot (69) formed in the shaft. This construc-

tion permits the shaft to move endwise, when adjusting the position of the carriage (58) without disturbing the rotary drive (67) and disk (68) connections. The gear (67) and disk (68) 5 are fastened together by a bolt (70) passing through the segmental slot (71) formed in the latter. By loosening the bolt and turning the hand wheel (72), fixed to right hand end of the shaft (65), the taping drum (2) may be rotatively adjusted about its 10 axis. When making this adjustment the hand wheel should be turned in the direction of rotation of the drum so as not to upset the gripper movement. The delivery 15 end of the machine is provided with an endless belt or chain (73) under which the blanks travel on a table (74) and which serves to press the adhesive strip firmly on the seam and give it time to set before the 20 blanks are discharged from the end of the table.

It will be understood that the specific construction and arrangement of parts herein shown and described may be changed or 25 modified without departing from the scope or spirit of this invention.

Having described the invention, what I claim is:

1. In a machine of the character described, 30 the combination of a rotary device for conveying a strip of tape to and applying it upon a blank, said device being mounted for continuous rotation in a fixed position, means for bodily adjusting said device 35 around its axis, and means for supporting and advancing a blank along a plane tangential to the periphery of said rotary device.
2. In a machine of the character described, 40 the combination of means for supporting a pile of blanks, means for successively delivering the lowermost blank from the pile, a rotary device for conveying a strip of tape to and applying it upon a blank, said 45 device being supported for continuous rotation in a fixed position and being bodily adjustable around its axis, and a feed roll associated with the blank delivering means 50 for advancing the delivered blank along a plane tangential to the periphery of said rotary device.

3. In a machine of the character described, the combination of means for feeding a tape, means for severing the tape into strips of desired length, a rotary taping device, means 55 for rotatively adjusting said device about its axis, and means for feeding a blank along a plane tangential to the periphery of the rotary device, said taping device being mounted for continuous rotation in a fixed 60 position relative to the blank feeding means and being adapted to successively engage the tape, convey the severed strip to the blank and apply it on a given line thereon, during each cycle of its operation. 65

4. In a machine of the character described, the combination of blank feeding means, means for intermittently feeding a tape, a rotary device having a tape severing mechanism associated therewith, said device being continuously rotated in a fixed position and being organized to successively engage the fed end of the tape, draw the tape, sever a strip of desired length therefrom while the tape is being drawn, convey the 75 severed strip to the blank, and apply it on a given line on the blank as the latter is being fed along a plane tangential to the periphery of the rotary device, during each 80 cycle of operation of said device, and means for rotatively adjusting the position of said device upon its axis.

5. In a machine of the character described, the combination of blank feeding means, means for feeding a tape, means for severing the tape into strips of desired length, a rotary drum provided with a gripper for 85 engaging the tape, a trip for throwing the gripper open to release the tape at the point of contact with the blank, and means for manually turning the drum around its axis 90 to adjust the position of the gripper relative to the trip and thereby position the drum for depositing the tape upon any given point on the blank. 95

In testimony whereof I have hereunto set my hand in the presence of two subscribing witnesses.

TOBIAS E. RAFFEL.
